New York

Application January 13, 1956, Serial No. 39,721

Term of patent 3½ years

(Cl. D44—15)

The figure is a plan view of a plate or similar article, showing my new design, the unit of repeat being contained between the broken lines, said unit being repeated about the circumference of the plate.

The plate is of a conventional configuration when viewed from the side and bottom thereof.

I claim:

The ornamental design for a plate or similar article, substantially as shown and described.
